CLAIM

The ornamental design for an in-store marketing sign, as shown and described.

DESCRIPTION

FIG. 1 is a front view of one embodiment of the in-store marketing sign.

FIG. 2 is a left side view of the in-store marketing sign embodiment of FIG. 1.

FIG. 3 is a right side view of the in-store marketing sign embodiment of FIG. 1.

FIG. 4 is a back view of the in-store marketing sign embodiment of FIG. 1.

FIG. 5 is a top view of the in-store marketing sign embodiment of FIG. 1.

FIG. 6 is a bottom view of the in-store marketing sign embodiment of FIG. 1.

FIG. 7 is a front view of a second embodiment of the in-store marketing sign.

FIG. 8 is a left side view of the in-store marketing sign embodiment of FIG. 7.

FIG. 9 is a right side view of the in-store marketing sign embodiment of FIG. 7.

FIG. 10 is a back view of the in-store marketing sign embodiment of FIG. 7.

FIG. 11 is a top view of the in-store marketing sign embodiment of FIG. 7.

FIG. 12 is a bottom view of the in-store marketing sign embodiment of FIG. 7.

FIG. 13 is a front view of a third embodiment of the in-store marketing sign.

FIG. 14 is a left side view of the in-store marketing sign embodiment of FIG. 13.

FIG. 15 is a right side view of the in-store marketing sign embodiment of FIG. 13.

FIG. 16 is a back view of the in-store marketing sign embodiment of FIG. 13.

FIG. 17 is a top view of the in-store marketing sign embodiment of FIG. 13; and,

FIG. 18 is a bottom view of the in-store marketing sign embodiment of FIG. 13.

The dash-dot-dash lines in FIGS. 1-6 and 13-18 form no part of the claimed design for the in-store marketing sign. The dotted lines in FIGS. 1, 7 and 13 represent scores that do form part of the claimed design for the in-store marketing sign. The solid vertical and horizontal lines spaced apart from the bottom edge and the right side edge in FIGS. 7 and 10 represent through cuts that do form part of the claimed design for the in-store marketing sign.
